BOWL

Clyde F. Adams, Hattiesburg, Miss.

Application August 30, 1950, Serial No. 11,989

Term of patent 14 years

(Cl. D36—2)

To all whom it may concern:

Be it known that I, Clyde F. Adams, a citizen of the United States of America, residing at Hattiesburg, Forrest County, and State of Mississippi, have invented a new, original, and ornamental Design for a Bowl, of which the following is a specification, reference being had to the accompanying drawing, forming part thereof.

Fig. 2 is a vertical sectional view thereof taken on line 2—2 of Fig. 1.

I claim:

The ornamental design for a bowl, as shown.
CLYDE F. ADAMS.
